OLOF THOMPSON, OF NEW YORK, N. Y.

MAGNET-LOCKING DEVICE.

1,404,910.

Specification of Letters Patent.

Patented Jan. 31, 1922.

Application filed November 10, 1917, Serial No. 201,358. Renewed December 15, 1921. Serial No. 522,722.

To all whom it may concern:

Be it known that I, OLOF THOMPSON, a citizen of Sweden, and a resident of the borough and county of Bronx, in the city and State of New York, have invented certain new and useful Improvements in Magnet-Locking Devices, of which the following is a specification.

This invention consists of a locking device 10 for electro-magnets, and includes mechanical means for temporarily retaining the core or cores of the latter, or a part carrying the same, in its or their inward position.

One object of the invention is to produce 15 a device of the nature set forth which shall operate to keep the movable part of a solenoid mechanically locked when drawn into closed position, so long as an electric current remains thereon, but will automatically release the said part and permit it to recede 20 to an open position whenever the flow of current is interrupted.

Another object is the production of a device 25 of the class mentioned capable of maintaining the operative part of a solenoid mechanically locked in the manner aforesaid, with but a fractional amount of the current expended to draw the said part to its closed position.

30 A further object is to provide a device of the character described which shall admit of adjustment so as to hold the working part of an electro-magnet temporarily locked at any suitable distance from the closing point 35 thereof, and subsequently to effect its release at a predetermined period.

A still further object is the provision of a 40 device of the type specified which shall obviate the necessity of accurate workmanship either in the manufacture or in the assembling of the various parts thereof, and yet will insure efficient and noiseless operation.

Still another object is to supply a device 45 of the species referred to, which shall be composed of few, simple and strong parts, easily kept in working order and repair.

Other objects and advantages will become apparent as the specification proceeds.

Electro-magnets heretofore employed for 50 opening or closing switches, and the like, have most always been subjected to hammering between the meeting ends of their cores, which obviously wrought injury to these parts, besides creating objectionable and disturbing noises. The defect here mentioned 55 is especially noticeable with magnets that

are energized by alternating electric currents, and is caused by the force acting against one or both of the cores, momentarily mastering the pull of the magnet, 60 which latter almost instantly recovers and overcomes the outward pull, thus bringing the core ends again quickly together. This action of the cores, rapidly breaking away and returning to contact with each other, 65 is disagreeably intensified when their opposed ends are not in absolute parallelism. For this reason, the meeting faces of the cores have had to be carefully scraped off to a bearing fit, one against the other, which 70 is a tedious and expensive operation, as only a competent mechanic of the highest class is capable of accomplishing this work, with studious application. Even then, the repeated impact due to occurring wear and 75 lost motion between the cores causes them eventually to lose their endwise alignment. Furthermore, a great deal of current is wasted, on account of it having to remain on the magnet coil with full force while the 80 cores are in their inward position, and besides a considerable heating up of the coil takes place, which also has an ill effect. The several disadvantages resulting from the employment of the old form of electro-magnets, above discussed, are done away with by 85 the present invention.

Generally described, the invention comprises a pair of electro-magnets of different power. The stronger one of these magnets 90 acts upon a core, or opposed cores, only one of which need be movable. An element capable of shifting the load to be moved carries the core acted upon mainly by the stronger magnet, the inward movement of 95 this element brings it under the control of a lock-mechanism operated with a reduced current flowing first through the weaker magnet. When the flow of current is interrupted, the lock releases the load pulling 100 element and the cores become separated. The final outward movement of the element may be utilized to re-establish the normal flow of the current to both magnets so that the cycle of operation will be repeated. 105

The advantages of the invention, as above briefly described, are best realized when all its features and instrumentalities are combined in the one and same structure, but useful combinations may be produced embodying less than the whole. 110

It will be obvious to persons skilled in the

art to which the invention appertains, upon becoming conversant with the details thereof, that the same may be incorporated in several different structures. Therefore, the accompanying drawings are submitted herewith as exhibiting only the preferred exemplifications of the invention.

In the said drawings:—

Fig. I gives a side view of one form 10 of the invention, the working parts thereof being shown in closed position;

Fig. II is a like view, with working parts in open position;

Fig. III is a view similar to Fig. I, representing a modified form of the invention, 15 with the working parts closed;

Fig. IV is a corresponding view of the latter named form, showing the working parts open as in Fig. II;

Fig. V is a front elevation or left-hand end view of the said modified form;

Fig. VI is a diagrammatic view of the electric wiring employed in the construction illustrated in Figs. III, IV and V;

Fig. VII is a side view of a further modification, with the working parts in a closed position;

Fig. VIII shows the same modified structure as the preceding view but with the 30 working parts in open position;

Fig. IX is a front or end elevation of the modified form shown in Figs. VII and VIII, as seen from the left hand side;

Fig. X is a diagram of the electric wiring 35 used in the modification last mentioned.

Fig. XI is a side elevation of an additional modification, a certain portion thereof being broken away, and the operative parts shown in closed position;

Fig. XII is a similar view of the same modified form of the invention, with the operative parts in open position; and

Fig. XIII is a front elevation of the last named modified form, as seen from the left 45 hand side of Fig. XII, a portion of a certain element being broken away.

Describing first that form of the invention which is illustrated in Figs. I and II, the numeral "1" denotes a frame appertaining to an electro-magnet of known construction. This frame usually consists of a casting comprising parallel sides, one of which only is shown, the same constituting the near side of the frame as seen in the two views referred to, and being joined to the opposite side by an elbow shaped or angular connecting piece 2, indicated by dotted lines. The said frame further includes superposed, integrally formed arms 3, 4, 5 shoulders 6, 7 and an abutment 8. Some of

60 these elements are provided in duplicate, that is, on both sides of the frame alike. Screw-threaded bosses 9 and 10 are formed in the back of the frame, near the top and bottom thereof respectively, for the recep-

tion of bolts wherewith the frame can be attached to a primary support.

Pivot pins 11 and 12 are supported transversely of the frame by the arms 4 and 5, respectively. Between the arms 3 and 4 is mounted a magnetic wire coil 15, which is held against the shoulders 6 and 7 in the rear, by means of clamps 16 and 17, fastened by screws to the outer ends of the latter named arms, in front. The coil 15 is designed to operate upon a pair of magnet cores consisting of two approximately equal parts 20, 21 which respectively enter it through its opposite ends. The parts 20 and 21 are secured at their outer extremities to levers 22 and 23, journalled on the before mentioned pivot-pins 11 and 12.

Forwardly of their pivots, the levers 22 and 23 are provided with fingers 24 and 25, extending oppositely therefrom so as to be 85 directed one toward the other. Preferably, the finger 24 is bent downwardly at the outer end to form a hook-shaped latch 26, adapted to take over a catch 27, on the upper side of the finger 25. As shown in Fig. II, 90 the latch and catch are disengaged, because the opposed cores 20 and 21 assumably have been parted by their respective levers 22 and 23 swinging by gravity both outward away from each other, owing to the electric current being cut out of the magnet 15. But when the latter is energized, to draw the two cores together into the position represented in Fig. I, then the levers 22 and 23 are swung both inward so that the latch 100 and catch become engaged.

On the inner edge of the lever 23, just above its pivot 12, is provided a stop 29, which comes into contact with the abutment 8, and prevents this lever from striking the magnet coil 15 with too much force, when the core 21 is pulled into its innermost position therein. The outermost limit of travel of the said lever 23 is regulated by means of an adjustable stop, consisting of a screw 110 30, threaded as at 28 into the lower end of the lever, inwardly of the pivot 12, and abutting against the underside of the transverse connecting piece 2 of the frame. The drop of the lever 22 is similarly limited by 115 a stop 31, formed on the underside thereof, rearwardly of the pivot 11, and arranged to bear upon the top edge of the said connecting piece. The lever 23 is further provided, on its outer edge with ears 32, one of 120 which only is shown, the same affording means of attachment for some object adapted for actuation by the lever, moved through the agency of the opposed cores controlled by the electro-magnet.

125 The distance from the centre of the pivot 11 to the offset of the latch 26 determines the extent of pull to be exerted by the magnetized coil 15 to keep the latch 26 and catch 27 engaged together, and so long as 130

the two latter are in this position, no electric current need be expended upon the core 21 to resist a load acting to pull out the thereto connected end of the lever 23. However, the current must remain on the coil 15, for otherwise, the weight of the levers 22 and 23 would cause them to separate and drop into their lowermost positions, as indicated in Fig. II. The advantage of using 10 the latch and catch, though the current remains on the magnet and cores, is that they constitute a lock preventing interrelative movement between the operative parts. The closer the latch and catch approach the center of the pivot 11, the less is the force required to keep them interlocked. When the said levers move inwardly towards each other, the lever 23 generally is the first to reach its limit of movement, due to the stop 20 29 thereon striking against the abutment 8 on the frame, and then the lever 22 completes its inward swinging stroke, whereupon the latch 26 takes over the catch 27 so as to be engaged thereby. As shown in 25 Fig. II, the latch 26 does not leave the extended end of the finger 25 beyond the catch 27, whenever it is disengaged.

The electrical energy required to be spent in order to maintain the said parts in engagement is considerably less than what is needed for the cores 20 and 21. Consequently, a very much weaker magnet could be used for the purpose, with a correspondingly diminished expenditure of electric 30 35 current, as in the forms of the invention hereinafter described.

A construction embodying this principle is disclosed in Figs. III to VI, inclusive. In these several views, all parts substantially 40 the equivalent of those already described are designated by the same reference characters, while such elements as involve material changes in form, location, or function are denoted by corresponding characters to which letter exponents have been suffixed.

Referring to the figures just named, the construction therein shown comprises a frame having parallel sides 1 and 1^a, connected by a transverse member 2^a. Projecting from the said frame, forwardly thereof, are arms 3, 4 and 5, preferably made integral therewith. Shoulders 6 and 7 are further formed on the frame. At the outer end of the arm 5 is an abutment 8^a. Bosses 9 and 10 are provided at the rear of the frame, the same being threaded to receive bolts which fasten the latter to a primary support. Pivot-pins 11 and 12 are 55 60 also fitted in the arms 4 and 5, transversely of the frame.

In the modification exemplified by Figs. III to VI, the electro-magnet is composed of two wire coils 15^a and 15^b, one made with few turns of heavy wire, and the other

having many turns of fine wire. As seen in Figs. III and IV, these coils are placed tandem, and held against the shoulders 6 and 7 by clamps 16 and 17.

Oppositely located cores 20 and 21 are 70 made to enter the said coils 15^a and 15^b, from the outer ends thereof, respectively. Fig. V indicates how each of these cores may be built up of laminated strips of metal, as 21^a, 21^b and 21^c, insulated from one another longitudinally. The cores are respectively secured, at their outer extremities, to levers 22 and 23, pivoted on the aforesaid pins 11 and 12.

A stop 29^a is provided on the outer edge 80 of the lever 23, near its lower end, in position to contact with a screw 30^a, adjustably set in the before mentioned abutment 8^a. A similar stop 31 projects from the underside of the lever 22, and limits the 85 latter's drop when abutting against the top edge of the transverse member 2^a of the frame.

Ears 32 are further provided on the outer edge of the lever 23, intermediately thereof, to furnish attaching means for an object 90 to be actuated, as in the form of the invention first above described. It is understood that this object represents a force opposing the inward movement of the lever 95 23, which overcomes the pulling strain upon it, through the action of the said magnet coils and cores.

At the lower, forward end of the lever 22 is provided a pair of fingers 33, depending 100 therefrom directly under the lever's fulcrum 11. These fingers act as a stop for the lever, limiting the upward swinging movement thereof by contact with the face of the transverse frame member 2^a.

In the hub of the said lever 22 is formed a ledge 34, between the fingers 33 above mentioned. Upon this ledge rests the upper end of a latch 35, made preferably of a hardened steel plate. This latch is guided 110 at its lower end and also near the middle on the shanks of screws 36 and 37, that are entered into suitable openings in the said transverse member 2^a. Around the screw 36 is placed a helical compression 115 spring 38, which bears with one end against the lower extremity of the latch 35, and is received at the other end in a recess 39, provided therefor in the member 2^a. A larger or slightly elongated aperture 40 is 120 made in this latch, at a substantially central point between the two screws 36, 37, through which aperture a rod 41 is passed. The forward end of the latter is adjustably received in a fork 42, hingedly connected 125 by a pin 43, to an ear 44, projecting inwardly from the lever 23.

When the electric current is turned off the magnetic coils 15^a and 15^b, and the lever 22 has dropped back upon the transverse mem- 130

ber 2^a as indicated in Fig. IV the ledge 34 assumes a position permitting the spring 38 to hold the latch 35 up straight against the under or rearwardly disposed side of the heads on the screws 36 and 37 so that the aperture 40 is then concentric with the rod 41, which may pass freely therethrough. But, when the current is turned on the coils 15^a and 15^b and the core 20 pulls the lever 22 into the position shown in Fig. III, the ledge 34 in that case is swung in a way to cause the latch 35 to tilt in a rearward direction, so that the top and bottom edges of the aperture 40 exert a binding action upon the rod 41, which is accentuated by the spring 38 tending to force the lower end of the latch 35 in the opposite direction. Thus the rod 41 and the lever 23 pivotally connected therewith are held and prevented from being pulled away by a load which the coils 15^a and 15^b would normally resist.

From one face, preferably the inner one of the transverse frame member 2^a, extends an ear 45 and to the latter is fulcrumed a lever 46, arranged to oscillate on the shank of a screw 47, entered into the said ear. Another screw 48 is also passed through the ear 45, above the screw 47. To the upper screw 48 is attached one terminal of a tension spring 49, the other end whereof is anchored as at 50, to the lever 46. The free end of the rod 41, which passes through the member 2^a, extends a sufficient distance rearwardly to be brought up against this lever and push back the same, so that the centre line of pull of the spring will pass the central alignment of the ear 45, screw 47 and point of connection 50. When this occurs, the spring 49 acts to complete the outward swing of the lever 46, until a nose or protuberance 51, located on the remote side of the fulcrum of the said lever, strikes against the rearwardly projecting end of the screw 48. The outward swing of the lever 46 is thereby limited, as shown in Fig. III. This movement of the lever is utilized to break a circuit passing through a shoe 52 and a pair of contact pieces 53, 54, carried in the lower portion of the frame member 2^a and properly insulated therefrom. The shoe 52 is held with interposed insulation, from the lower end of the lever 46. An electric wire 57 leads from the contact 53 to the junction between the windings of the coils 15^a and 15^b, as indicated at 58, Fig. VI. The numeral 59 denotes one of the line wires to which the contact 54, and the end wire of the coil 15^b are connected, the latter as at 60. The other line wire, designated by the numeral 61, is connected to the end wire of the coil 15^a, as at 62.

When the lever 46 stands in the position shown in Fig. III, and also indicated by full lines in Fig. VI, the electric current must pass through the coil 15^b, from its outer end 60, and thence flow through the heavier coil

15^a which at that time is in series therewith. The coil 15^b, as previously stated has many turns of fine wire and therefore lets through or consumes but a very small amount of current. Hence this coil 15^b will only require a fractional part of the power expended to hold the cores 20 and 21 together, after they have been brought to this position, as compared with the amount spent to pull up, initially, the loaded core 21 against the core 20. This is because, when the cores are in their closed position, the latch 35 has a grip on the rod 41, and prevents the parting of the core 21, with its lever 23, from the core 20. But, as soon as one of the line wires 59 and 61 is cut out, the overbalanced levers 22 and 23 swing outwardly, and the ledge 34 as before explained, moves away from the upper edge of the latch 35, which is thereby enabled to align itself perpendicularly upon the shanks of the screws 36 and 37, so that the top and bottom edges of the aperture 40 loosen their grip on the rod 41. As the latter moves outwardly at that time, it is arranged to reset the lever 46 in its previous position by means of a screw 63, adjustably held in the end of the rod, in axial alignment therewith. This screw is positioned so as to strike with the underside of its head against the back of the lever 46, which then advances to the position represented in Fig. IV whereupon the shoe 52 closes the gap intervening between it and the contacts 53, 54, the coil 15^b is short circuited, i. e. placed in shunt relation to the line 58, 57 and 59, and the electric current flows along a more commodious and direct path through the said coil 15^a. When this coil becomes energized, it exerts its torque primarily upon the core 21, and subsequently on the core 20, whereby the cycle of operation is repeated, the latch 35 again locking with the rod 41 mechanically.

The outward swing drop of the lever 23 is predetermined by the adjustment of the screw 30^a against the stop 29^a. In this modified construction, the core 20 is arranged to move into inward position first, and is immediately met by the core 21. The precise time at which the end of the rod 41 is to hit the front edge of the lever 46 or the head of the screw 63 will pull or press back against the rear edge of the same lever, can be accurately regulated to cause the said cores to approach each other within any required distance, the mechanical locking of the parts taking place directly after the electric current has been deviated to enter the weaker magnet first, when the magnet coils are in series. At this moment, a slight outward movement of the core 21 occurs, which is indicated at 64 Fig. III, and serves further to increase the binding action of the rod 41 against the gripping edges of the aperture 40 in the latch 35.

In Figs. VII, VIII, IX and X, is repre-

sented a mode of construction showing how the weaker or minor electro-magnet can be placed apart from the stronger or major one, and made to operate as well on the 5 mechanical lock mechanism in a direct manner, while both magnets are floating upon or connected up with the same circuit. In this exemplification of the invention, the frame comprises parallel sides 1^b and 1^c , 10 joined by a connecting piece 2^b and provided with arms 3 a , 4 and 5 preferably integral therewith. Bosses 9 are formed on the sides of this frame, with suitable apertures for bolts to hold it to a primary support. Pivot 15 pins 11 a and 12 are fitted across the arms 4 and 5 respectively.

A major or relatively strong electro-magnet 15 e with few turns of heavy wire, is placed in the upper part of the frame, and 20 a minor or relatively weak electro-magnet, with many turns of fine wire is located in the lower part of the same. The latter-named magnet may consist of a single wire coil 15 a , as shown, in Fig. VIII, or of three coils 25 15 c , 15 f , and 15 g , such as appertain to a three phase electro-magnet, and are illustrated in Fig. VII.

The magnet 15 e is held by a clamp 17, fastening it against the arm 3 a . This major 30 magnet is designed to act upon opposed cores 20 a and 21. The core 20 a is rigidly attached to the arm 3 a and therefore immovable, while the core 21 is carried by a lever 23, fulcrumed on the pivot pin 12.

35 A bell crank lever is pivoted on the pin 11 a , with its short arm 24 a turned towards a finger 25 projecting from the inner edge of the lever 23. The arm 24 a is formed with an overhung latch 26, adapted to engage a catch 40 27 on the finger 25, when the core 21, is energized to pull the lever 23 into the position represented in Fig. VII.

The lever 23 is provided on its outer edge with a pair of ears 32, which in the present 45 modification are located directly opposite the finger 25 formed on the inner edge of the lever. As in the other forms of the invention hereinbefore described, the ears 32 afford a means of connection between the lever 23, with its movable core 21, and the object to be pulled or shifted.

The longer arm 66 of the bell-crank lever aforesaid is connected as at 67 with the core 50 of the minor magnet, whether the latter be of the species 15 d , Fig. VIII, or of the species 15 e 15 f 15 g , Fig. VII. In the case of the three phase system, the core consists of double hollow cylinders as 68 a , 68 b , of different metals, according to approved practice. The 55 single core of the magnet 15 d is indicated by the numeral 68. The coils 15 e , 15 f , 15 g are set in a shell or casing 69, provided therefor at the lower end of the frame members 1 b and 1 c . A cover 70 forms a closure for 60 this shell, in front. As represented in Figs.

VII and VIII, a screw 30 carried by an extension 28 projecting rearwardly from the lower end of the lever 23 is arranged so as to be swung into contact with the underside of the same shell, and thereby operates to limit 70 the outward swing of the lever 23, to which the core 21 is attached.

In the wiring diagram, Fig. X, which corresponds to the arrangement of parts illustrated in Fig. VII, the numerals 75, 76 and 77 respectively designate line wires of a three phase system. As shown, the wire 77 is connected up with one terminal of the coil 15 e ; the wire 76 is similarly connected with the coil 15 f ; and the wire 75 has a corresponding connection with the coil 15 g , including a switch 78 therebetween. The other terminal wires for these three coils are respectively represented by the lines marked 79, 80 and 81 which are connected to a common header 82. The numerals 83 and 84 designate the terminal wires for the major magnet 15 e , which are arranged to connect with the previously mentioned wires 75 and 76 respectively, the wire 83 being coupled up 80 by means of a switch 85. Whenever the connection between this switch and the wire 75 is severed, the electric current is taken off the major magnet 15 e , so that it has no further work to do than to pull in the core 21 95 to its closed position. But, by reason of the fact that the current stays on the coils 15 e , 15 f , 15 g , of the minor magnet, the double core 68 a , 68 b within the latter draws the longer arm 66 of the bell-crank sufficiently 100 for the catch 26 to take over the latch 27, and keep the lever 23 from dropping. In this way a considerable saving of electric current is effected, over having it remain on the major magnet for the entire period during 105 which the movable core remains therein. Notwithstanding that separate switches 78 and 85 have been shown for the operation of the major and minor magnets in this modified construction, it will be readily perceived that the automatic current switching arrangement diagrammed in Fig. VI can as 110 well be used in conjunction with this modification.

An additional modification of the invention is shown in Figs. XI, XII and XIII. In this modified form of the invention, the frame is composed of similarly constructed sides 1^a and 1^c , united by upper and lower connecting pieces 2^a and 2^c . The sides are 120 formed with arms 3 a , 4 and 5, and the frame is held as a whole to a primary support by means of suitable bolts passing through bosses 9, on the opposite sides. Pivot pins 11 a and 12 are supported in the arms 4 and 125 5, respectively. Above the arms 4 is mounted a major electromagnet 15 e , abutting at its rear end against the arm 3 a and held in front by a clamp 17. A fixed core 20 a projects forwardly from the arm 3 a , opposite a 130

movable core 21, carried by the upper end of an overbalanced lever 23, pivoted at its lower end on the pin 12. On the pin 11^a is fulcrumed a bell crank lever having a short 5 arm 24^a extending towards the lever 23. A finger 25, projecting inwardly from the latter is extended under the said short arm, which is formed with a hook-shaped catch 26, adapted to engage a correspondingly 10 shaped latch 27, on the said finger. These parts are so constructed that the latch when disengaged from the catch, will ride and rest upon the rearwardly extended end of the finger in the plane of oscillation of the lever 23, that carries the movable core 21. At 15 the lower end of the lever 23, is an extension 28, carrying a stop in the form of a screw 30, adjustably set therein so as to come into contact with the underside of the lower 20 connecting piece 2^a of the frame, and limit the drop of the said lever, when the core 21 is liberated by the magnet 15^c and the catch is released by the latch. Ears 32 provided externally on the lever 23, supply the same 25 means of attachment for the load to be moved, as with the other forms of construction hereinbefore described.

The longer arm 66 of the aforementioned bell-crank lever has formed integral therewith, at its lower extremity a gear segment 87, with teeth meshing into a pinion 88, secured to a shaft 89, journalled in bearings 90, transversely of the frame. Upon the shaft 89 is mounted a rotor disc 91, between 30 laminations 92, 93 carried by the bearings 90 on both sides thereof, all of which pertain to an induction motor, of ordinary construction. Oppositely connected windings 94, 95 of a two phase system, with terminal 35 wires 96, 97 respectively leading therefrom, are placed intermediately of the laminations. Terminal wires 98, 99 likewise lead from the electromagnet 15^c.

When the electric current is afforded a 40 continuous flow through the wires 98, 99, the magnet 15^c becomes energized and the core 21 actuated thereby pulls the lever 23 inwardly against a load imposed upon the latter, at 32, for instance. In the meanwhile, 45 the electric current is caused to flow uninterruptedly also along the wires 96, 97 of the induction motor, tending to rotate the pinion 88 in the direction indicated by the arrow "A" in Figs. XI and XII. The 50 pinion is held in check, however, by the inactivity of the bell-crank lever, when the hook portion of the catch 26 rides upon the inner end of the finger 25. But, as soon as the finger, with its latch 27, arrives at the 55 point where it can be engaged by the catch, the rotation of the pinion causes the shorter arm 24^a of the bell-crank lever to be lowered sufficiently to permit engagement. While 60 the current remains on both windings 94 and 95, the longer arm 66 of the bell-crank 65

lever is held in the position represented in Fig. XI whereby the load moving lever 23 is kept in quiescence, even though the current be turned off the major magnet 15^c. But, if the flow of current through either 70 one of the terminal wires 96 and 97 is interrupted, the other terminal then becomes unable to hold the latch and catch engaged, and the overbalancing of the lever 23 forces them apart. It is understood that when the 75 current is taken off either wire, 96 or 97 it has been previously deviated from the magnet 15^c.

Although no separate wiring diagram has 80 been furnished in connection with the structure exemplified in Figs. XI to XIII, it is obvious that the same can be electrically connected up according to either of the systems represented in Figs. VI and X.

While certain preferred embodiments of 85 this invention have been shown and described, it will be understood that changes in the form, arrangements, sizes, proportions and details thereof may be made without departing from the scope of the invention as defined by the appended claims.

Having described my invention what I desire to secure by Letters Patent and claim is:—

1. A device of the class described comprising, in combination, a load-moving element including a core oscillatable therewith, an electro-magnet acting thereupon, and mechanical means positively maintaining the core stationary within said magnet 95 as long as the latter is energized.

2. A device of the class described including, in combination, an electro-magnet, a core adapted to be shifted thereby, an oscillatable element carrying said core, and mechanism coincidently oscillating with said element assisting to retain the core inward during magnetization.

3. A device of the class described including, in combination, an electro-magnet, a core drawn arcuately thereinto, a load pulling element carried by said core towards said magnet, and mechanical means coacting with the latter to retain said element with the core in its inward position while it remains energized.

4. A device of the class described including, in combination, a load actuating element, an electro-magnet moving the same, and automatically applied means assisting 110 the energized magnet in maintaining said element in a predetermined location, said means being self-releasing when the magnet is deenergized.

5. A device of the class described including, in combination, an electro-magnet, a load moving element actuated thereby, and conjoined electrical and mechanical means locking said element after actuation, the arrangement being such that the force of the 120 125 130

magnet pulls the load with the element and sets the lock, whereafter the energy expended from said magnet to maintain the element in place is limited to holding the 5 lock set, said means comprising a retaining mechanism attached to said load-moving element and an operative connection between the magnet and said mechanism.

6. A device of the class described comprising, in combination, a load moving element including a core, an actuating electro-magnet therefor, and retaining means operating to hold said element with the core in conjunction with the energized magnet, the 10 arrangement of the weight of the element and said core permitting self-release thereof from said means when the said magnet is deenergized.

7. A device of the class described including, in combination, a pair of electro-magnets of different power, a load moving element actuated thereby, a mechanical retainer engaging said element, and means for reducing the flow of electric current through 25 said magnets, the reduced current serving to maintain the engagement of said retainer with the element.

8. A device of the class described including, in combination, a major electro-magnet, 30 a minor electro-magnet operable therewith either in shunt or in series, a load shifting element moved by said magnets while in shunt relation, a mechanical retainer engaging said element during the latter part of 35 its advance, and means operating automatically to place the magnets in series, thereby causing the element to be kept engaged.

9. A device of the class described comprising, in combination, an electro-magnet, 40 a load actuating element including a core drawn by said magnet, and a retainer moved in the same direction as said core coacting mechanically with the energized magnet in maintaining said element with the core in 45 a given position, said retainer automatically effecting the release of the latter prior to the retraction thereof upon demagnetization.

10. A device of the class described including, in combination, an electro-magnet, a 50 core actuated thereby, a support carrying said core tending to retract the same, and a retainer on said support counteracting the retraction of and holding said support engaged while the energized core remains in an inward position, said retainer being movable together with the core and its support toward and from the same end of said magnet.

11. A device of the class described including, in combination, electro-magnets of different strength, a core common to both magnets arranged to be pulled mainly by the stronger one thereof, a support tending to retract said core, and a lock retaining said support chiefly through the agency of the 65 weaker magnet.

12. A device of the class described including, in combination, electro-magnets of different strength, a core actuated mainly by the stronger magnet, a support for said core tending to effect retraction thereof, a 70 retainer engaging said support following the core's actuation, and electrical connections operating to hold said retainer in engagement by directing the electric current through the weaker magnet, the release of 75 the support from the retainer automatically taking place after the electric circuit has been interrupted.

13. A device of the class described including, in combination, major and minor 80 electro-magnets placed in axial alignment one relatively to the other, opposed cores arranged to enter said magnets from the outer ends thereof, a load actuating element moved principally by the core of the major 85 magnet, a retainer engaging said element during the latter part of the movement of said core, and an electric connection automatically operating to direct the current first to the minor magnet upon the element 90 becoming engaged by said retainer.

14. A device of the class described including, in combination, electro-magnets of different strength mounted at a distance one from the other, a core actuated by the 95 stronger magnet, a load moving element carrying said core, a retainer engaging said element during the latter part of the advance thereof, and means primarily controlled by the minor magnet operable to 100 maintain the element and said retainer in engagement, said means serving to direct the electric current first to the weaker magnet after such engagement is effected.

15. A device of the class described including, in combination, an electro-magnet, a core actuated thereby, a support for said core tending to effect retraction thereof, a retainer engaging said support after the core is drawn inward, and operative connections 110 serving alternately to keep the electric current on said magnet during engagement of said retainer with the support, and to turn it off for the release of the retainer.

16. A device of the class described including in combination, electro-magnets of different power, a core moved mainly by the stronger magnet, a support elevated by said core, a retainer engaging said support when the latter is raised, an electric circuit encompassing both of said magnets and admitting of being primarily directed through the weaker magnet, and means operating to direct said circuit to the latter named magnet to maintain said retainer in engagement 120 with the support, the breaking of the circuit releasing the hold of the retainer on the support and permitting the latter to drop, whereafter rehabilitation of the full circuit is effected.

17. A device of the class described including, in combination, an electro-magnet, cores entering the same from the opposite ends thereof, supports respectively carrying said cores tending to effect retraction thereof, and self-parting means for retaining said supports together while the cores remain energized.

18. A device of the class described including, in combination, an electro-magnet, a load moving element actuated thereby, a retainer with a guide carried by said element, and a locking part held constantly in superposed contact with said guide so as to automatically engage said retainer following actuation of the element.

19. A device of the class described including, in combination, an electro-magnet, opposed cores actuated thereby, levers respectively carrying said cores, a locking part on one of said levers, and a retainer on the other lever arranged to engage said part when the cores are drawn together.

20. A device of the class described including, in combination, one or more electro-magnets, a pair of opposed cores actuated thereby, pivoted levers respectively carrying said cores, a retainer connected up with one of said levers, and a locking part capable of exerting a binding action upon said retainer, said part having a connection with the other lever whereby the locking part is brought into action when the cores are being moved inward.

21. A device of the class described including, in combination, electro-magnets of different strength in circuit together, a load moving element actuated mainly by the stronger magnet, a retainer carried by said element, a locking part adapted to be engaged by said retainer, and a shiftable member acted upon by the retainer whereby the electric current is deviated so that said part can be maintained in position chiefly by the weaker magnet.

22. A device of the class described including, in combination, electro-magnets of different power, an electric circuit therefor, opposed cores actuated primarily by the stronger magnet, levers respectively carrying said cores and tending to effect retraction thereof, a pair of locking members adapted to retain one of said levers in its inward position, said members being caused to engage each other when the levers are oscillated inwardly with their respective cores drawn together, and a shifter in said circuit acted upon by one member so as to direct the current first through the weaker magnet and cause it to retain said member in engagement with the other member.

23. A device of the class described including, in combination, electro-magnets of different strength in circuit together, a load moving element actuated mainly by the

stronger magnet, a pair of locking members adapted to retain said element in its inward position, a shifter acted upon by one of said members whereby the electric current is deviated to maintain the other member engaged chiefly through the weaker magnet until an interruption occurs in the circuit, and resetting means for re-establishing the circuit also operated by the last named member upon release thereof by the first named member.

24. A device of the class described including, in combination, electro-magnets of different power, an electric circuit therefor, a load moving element actuated mainly by the stronger magnet, a retainer carried by said element, a locking part arranged to meet said retainer and to be maintained in engagement therewith chiefly by the weaker magnet, and means on the retainer adapting it to change said circuit by directing the electric current first through each magnet in alternation.

25. A device of the class described including, in combination, superposed magnets of different strength, a load moving element actuated by the stronger magnet, a retainer carried by said element, and a lever pivoted intermediately of said magnets, said lever having one arm designed to engage said retainer and its other arm operatively engaged by the core of the weaker magnet.

26. A device of the character described comprising in combination, a pair of pivoted levers, one of which is adapted to moving a load and the other has arms of unequal lengths, opposed cores respectively carried by said levers, electrical means for drawing said cores with the levers one towards the other, and retaining elements operating to keep the latter locked in their inward position, said elements being respectively located intermediately of the load-moving lever and on the shorter arm of the other lever, the arrangement being such that while the current remains on the core of the lever opposed to the one moving the load, only so much of the current is required to retain the load as will keep said elements together, irrespective of the outward pull on the core of the load moving lever.

27. A device of the character described comprising in combination, a pair of levers pivoted so as to be overbalanced away from each other, opposed cores respectively carried at the upper ends of said levers, electrical means for drawing said cores with the levers substantially together, and retaining elements between the levers operating to keep the same locked in their inward position while the current remains on the cores, and becoming disengaged upon the interruption thereof, whereafter the levers are released and permitted to swing outwardly.

28. A device of the character described comprising in combination, a pair of overbalanced levers pivoted to oscillate oppositely one to the other, cores on said levers adapted to be brought together, electrical means actuating said cores, and retaining elements on the overbalanced levers arranged to become interlocked so as to hold the latter when the cores have been drawn inward, but parting automatically with the levers after the current is cut out.
29. A device of the character described comprising in combination, a pair of levers oscillatable one toward the other, an electro-magnet positioned intermediate of said levers, cores on the latter arranged to be drawn substantially together by said magnet, and automatically operated retaining elements adapted to interlock following inward oscillation of the levers.
30. A device of the character described comprising in combination, a load moving lever having its fulcrum substantially at one end, a core carried by said lever at the end remote from said fulcrum, an electromagnet adapted to actuate said core, and retaining means for the lever intermediate the ends thereof arranged to hold it in a predetermined position when said magnet is energized and to release the same upon the current being interrupted.
31. A device of the character described comprising in combination, a pair of pivoted levers with opposed ends normally kept apart by gravity, cores respectively carried by said ends of the levers away from the pivots thereof, an electromagnet adapted to draw said cores substantially together, and self-parting retaining elements nearer the pivots of said levers arranged to interlock after the magnetized cores have approached each other and to be released with the levers as the cores are deenergized.
32. A device of the character described comprising in combination, a pair of levers arranged to oscillate on independent fulcrums oppositely one to the other, cores on opposed ends of said levers, electrical means functioned to draw said cores substantially together, and coacting retainers for the levers capable of locking the same immediately of their said fulcrums.
33. A device of the character described comprising in combination, a pair of levers oscillatable toward and away from each other, opposed cores near the ends of said levers, electrical means adapted to draw said cores substantially together, and self-parting retainers for the levers brought into engagement by inward oscillation of the latter through the action of said means, one of said retainers being located intermediate the ends of one lever, and the other retainer tiltable thereagainst beyond the fulcrum of the second lever.
34. A device of the character described comprising in combination, a pair of levers oscillatable oppositely one to the other, cores on said levers, an electro-magnet adapted to draw in said cores, and coacting retaining elements projecting inwardly in tilting arrangement from said levers, said elements becoming interlocked when the cores have been brought to their inner position by the energized magnet, and parting automatically with the levers as the cores are demagnetized.
35. A device of the character described comprising in combination, a lever fulcrumed near one end, a core attached to the other end thereof, a load moving connection on said lever intermediate of its fulcrum and said core, an electromagnet actuating the latter, and a retainer for the lever acting thereupon in a direction to oppose the pull of the load.
36. A device of the character described comprising in combination, a load shifting lever pivoted substantially at one end, a core carried by the other end thereof, an electro-magnet actuating said core, and retaining elements functioned to hold said lever when the core has been drawn inward by said magnet, one of said elements being connected to move with the lever and to be engaged by the other element in a plane at substantially right angles to the line of movement.
37. A device of the character described comprising in combination a pair of levers of different lengths pivoted one above the other, cores carried by opposed ends of said levers, an electromagnet arranged to draw said cores substantially together, and retaining elements for holding the levers interlocked when the cores have been brought to their inward position, said elements being located below the pivot of the shorter lever and to one side of the longer lever.
38. A device of the character described comprising in combination, a pair of oppositely oscillatable levers pivoted in superposed relation, cores carried by said levers, an electromagnet adapted to draw said cores substantially together, and interlocking retaining elements extending one through the other in substantially right angular arrangement.
39. A device of the character described comprising in combination, an electromagnet, cores adapted to be drawn one towards the other by the magnet, levers of diverse lengths actuated by said cores and pivoted in variant relation thereto so as to have a differential oscillatory motion to and away from each other, and retaining elements coacting with said levers to interlock the same when pulled inward, the longer and slower moving lever being the first to reach its inner position while the shorter and quicker

swinging lever moves out first when the de- energized magnet releases the cores.

40. A device of the character described comprising in combination, a pair of levers oscillatable one towards the other, oppositely directed cores carried thereby, an electromagnet adapted to draw said cores substantially together, and retaining elements arranged to interlock when the levers have been drawn inward, said levers being pivoted below their respective centres of gravity and offset from the point of retention of said elements.

41. A device of the character described comprising in combination, a pair of levers pivoted to oscillate one toward the other, cores carried thereby, an electromagnet arranged to draw in said levers, retaining elements adapted to interlock upon inward movement of said levers, and means operating to limit the oscillatory motion of the latter so as to control the positions of said elements.

42. A device of the character described comprising in combination, a pair of oppositely swinging levers, cores carried thereby, an electromagnet adapted to actuate said cores, retaining elements capable of interlocking said levers after the cores have been actuated, and stops arranged to limit the outward swing of the levers when released by said elements subsequently to the cores being deenergized.

43. A device of the character described comprising in combination, a lever, a core carried thereby, an electromagnet capable of actuating said core, a retainer coacting with the latter in holding said lever in a predetermined position, and a stop operating subsequently to demagnetization of the core, and release of said retainer to limit the movement of the lever in a direction opposite that to which it was brought by the action of said magnet on the core.

44. A device of the character described comprising in combination, an overbalanced lever pivoted near its lower end, a core carried by the upper end thereof, an electromagnet adapted to draw said core, a retainer coacting with the core in maintaining said lever in its inward position, and a stop serving to check the outward swing of the lever following liberation of said retainer through deenergizing of the core.

45. A device of the character described comprising in combination, a pair of oppositely oscillatable levers, cores respectively carried by the latter, an electromagnet capable of drawing said cores substantially together, one of said levers being adapted to move a load and provided with a catch, and a stop operating to arrest the load moving lever in advance of said other lever thereby

placing the catch in position to be engaged by said latch upon completion of the movement of the last named lever.

46. A device of the character described comprising in combination, a load moving lever, a core carried thereby, an electromagnet adapted to actuate said core, a retainer cooperating with the latter to hold said lever in a given position, stops respectively located on opposite sides of the fulcrum of the lever to check it in either direction relatively to the point of retention, and means serving to change the contacting distance between said stops and thereby limit the movement of the lever.

47. A device of the character described comprising in combination, a frame having spaced arms at different distances apart, an electromagnet supported therefrom, cores arranged to be drawn substantially together by the latter, and levers carrying said cores pivoted in the arms remote from said magnet.

48. A device of the character described comprising in combination, a frame provided with sets of arms spaced from one another, an electromagnet at one end of said frame, oppositely oscillatable levers pivoted to said arms, one at the end of the frame remote from said magnet and the other intermediately thereof, and cores on said levers positioned to be actuated by said magnet.

49. A device of the character described comprising in combination, an open frame, an electromagnet in the upper part of the same, a load moving lever pivoted to swing exteriorly of said frame from the lower part thereof, another lever pivoted to oscillate within the frame oppositely to said first named lever, cores respectively carried by both levers in position to be acted upon by said magnet, and intermediate elements co-operating to retain the levers while said cores are held magnetically together.

50. A device of the character described comprising in combination, a frame with arms extending forwardly therefrom at different elevations, an electromagnet supported from the uppermost set of arms of said frame, a load moving lever pivoted to the lowermost arms so as to oscillate in front of said magnet, a coacting lever pivoted to the intermediate arms in position to swing in rear of the magnet concurrently with said load moving lever, cores on both of said levers arranged to be drawn in by the magnet from the opposite ends thereof, and a pair of retaining elements operating in a median plane between said arms to hold the levers inward while the cores are energized.

OLOF THOMPSON.
